US0D1039645S

(12) **United States Design Patent** (10) **Patent No.:** **US D1,039,645 S**
(45) **Date of Patent:** **** Aug. 20, 2024**

(54) **PROJECTILE CASSETTE**

(71) Applicant: **Wrap Technologies, Inc.**, Tempe, AZ (US)

(72) Inventors: **Milan Cerovic**, Tempe, AZ (US); **David T. Richter**, Tempe, AZ (US)

(73) Assignee: **Wrap Technologies, Inc.**, Tempe, AZ (US)

(**) Term: **15 Years**

(21) Appl. No.: **29/802,113**

(22) Filed: **Aug. 3, 2021**

(51) LOC (14) Cl. **22-01**

(52) U.S. Cl.

USPC **D22/100**

(58) **Field of Classification Search**

USPC D13/118, 184; D22/100, 117, 199

CPC F42B 12/66; F41H 13/0006

See application file for complete search history.

(57) **CLAIM**

The ornamental design for the projectile cassette, as shown and described.

DESCRIPTION

FIG. 1 is a perspective view of a projectile cassette in accordance with our invention;

FIG. 2 is a top view thereof, an opposing bottom view being a mirror image thereof;

FIG. 3 is a side view thereof, an opposing side view being a mirror image thereof;

FIG. 4 is a front view thereof; and,

FIG. 5 is a rear view thereof.

The dashed lines in the drawings show environmental structure and form no part of the claimed design.

1 Claim, 3 Drawing Sheets
